UNITED STATES PATENT OFFICE.

FRANCIS H. TREAT, OF CLEVELAND, OHIO, ASSIGNOR TO DUFF PATENTS COMPANY, INCORPORATED, OF PITTSBURGH, PENNSYLVANIA, A CORPORATION OF PENNSYLVANIA.

GAS PRODUCER.

Application filed May 25, 1920. Serial No. 384,053.

To all whom it may concern:

Be it known that I, FRANCIS H. TREAT, a citizen of the United States, residing at Cleveland, in the county of Cuyahoga, and

5 State of Ohio, have invented a new and useful Improvement in Gas Producers, of which the following is a full, clear, and exact description, reference being had to the accompanying drawings, forming part of this
10 specification, in which—

Figure 1 is a view partly in vertical section and partly in side elevation of a gas producer embodying my invention.

Figure 2 is a plan view, partly in section
15 of the parts shown in Figure 1.

Figure 3 is a plan view, partly broken away, of the ash pan and its associated parts.

Figure 4 is a section on the line IV—IV
of Figure 3.

20 Figures 5 and 6 are detail sectional views taken respectively on the lines V—V and VI—VI of Figures 2 and 3, and

Figure 7 is a cross section through one of the tuyères.

25 My invention has relation to certain new and useful improvements in gas producers.

One of the objects of my invention is to provide a gas producer in which the usual grate construction is eliminated and to pro-

30 vide in lieu thereof a novel and effective arrangement of blast distributing tuyères which are so constructed and arranged as to impose a minimum resistance to the descent of the ash and fuel bed in the producer,

35 while at the same time they give an effective distribution of the blast throughout the fuel bed.

40 A further object of my invention is to provide a gas producer of the stationary type having means of novel and effective character for removing ashes from the stationary ash pan into which the producer discharges its ashes.

45 A further object of the invention is to provide novel means for supporting the shell and body of the producer.

The nature of my invention will be best understood by reference to the accompanying drawings in which I have shown a preferred
50 embodiment thereof and which will now be described, it being premised, however, that various changes can be made in the details of construction, arrangement and combination of the various parts, without departing

from the spirit and scope of my invention as 55 defined in the appended claims.

In these drawings, the numeral 2 designates the shell of the producer which may be, in general, of any suitable character. This shell, together with the entire body of 60 the producer, is supported by means of the columns 3, preferably of structural steel. The bases of these columns are offset sufficiently with respect to the vertical line of the producer shell and of the ash pan and its associated parts, to be clear of the latter, their upper portions being bent inwardly and secured to the shell by means of the plates 4. As many of these columns may be provided around the producer as is necessary in any 70 particular case.

5 designates a radial series of tuyères which are designed to replace the grates usually employed. These tuyères are equally spaced, projecting inwardly through the depending mantle or apron 6 at the base of the producer, being removably seated in openings therein and supported by the brackets 7 secured to the inner side of the apron or mantle. Each tuyère is also preferably provided with a downwardly projecting flange 8 which fits the outer upward portion of the apron or mantle. In the particular form shown, these tuyères are of circular cross-section and are provided at their under 85 sides with air distributing holes 9 arranged in two longitudinal series preferably at opposite sides of the center of the tuyère. The inner ends of the tuyères are provided with downwardly and inwardly extending discharge openings 10. Each tuyère may be supplied with blast by any suitable arrangement such as a steam jet blower 11 of well known character.

Owing to the circular form of these 95 tuyères and their spaced arrangement, it will be seen that they afford a minimum resistance to the free passage of the ash downwardly between them, while giving a very effective distribution of the blast.

100 12 designates a stationary ash pan mounted on suitable supports 13 of the foundation and into which the mantle or apron 6 depends to a distance below the water level of the pan sufficient to provide the usual 105 water seal. The ash pan has an up-standing edge 12' whereby the pan may hold the desired amount of water.

14 designates two rotary scrapers which are arranged to turn within the ash pan and to deliver ashes over the peripheral edge thereof. These scrapers are arranged oppositely to each other so as to give a balanced action. They are preferably of the spiral or curved form, approximately as shown, their inner ends being secured to the central hub 15. This hub is loosely mounted around the centrally fixed water discharge pipe 16 which extends upwardly into the pan and within the cap 17, a plurality of openings 17^a being provided through which the water can enter said cap, and thence pass into the discharge pipe 16. From the hub out to a point adjacent to the periphery of the bottom of the pan, the scrapers consist of flat sections which are arranged to rotate adjacent to the bottom of the pan. At this point 20 they merge into the inclined portions 18 which extend obliquely upward along the sloping sides of the pan and to the outer periphery of its upper edge. The ends of the portions 18 are rigidly secured to posts 20 which at their lower ends are secured to the inner side of an annular ring 21 which surrounds the pan. This ring is mounted on a plurality of wheels 22 journaled therein and which travel on a circular track 23 on the foundation. A portion of the outer periphery of the ring is formed with gear teeth 24 which are engaged by driving pinions 25. These driving pinions are journaled at the upper ends of the short vertical shafts 26. 30 Each of these shafts carries a beveled gear wheel 27 which meshes with a beveled pinion 28 on a diametrically extending shaft 29 driven by any suitable means, such as the electric motor 30. The gear ring 21 is centered between the two pinions 25 and these pinions are prevented from meshing too deeply by means of guide wheels or rollers 31 which travel on the untoothed peripheral portion of the ring 21. From the foregoing, 40 it will be apparent that the ring 21, together with the scrapers, rotate as a unit with respect to the stationary pan.

32 designates an ash receiving trough which is mounted on the upper peripheral portions of the wheels 22 before referred to in a manner to be rotated around the ash pan by said wheels. As will be apparent, the trough will be rotated at approximately twice the speed of the peripheral movement of the ring. This trough is arranged to receive the ashes which are discharged over the upper edge of the pan by the action of the scrapers.

The ashes are discharged from its trough at 60 a single point by a suitable plow, such as now to be described.

33 designates a plow which is supported by a fixed frame member 34 secured to and depending from the producer shell, and 65 which is arranged to work within the trough

in a manner to scoop up the ashes and carry them over the edge of the trough as the latter rotates.

35 designates a guard adjacent to the plow, and which acts to direct the ashes to the action of the plow and to prevent their becoming lodged at the extreme inner edge of the trough. The manner in which the plow is constructed and arranged is clearly shown in Figures 2, 5, and 6. As the trough 70 rotates in a clockwise direction, the ashes are caught upon the oblique inclined blade portion 33^a thereof and are forced upwardly, being finally discharged at the upper edge 75 of said inclined portion at the point 33^b in Figure 2.

In this manner I provide a simple and very effective arrangement whereby notwithstanding the non-rotation of the producer and ash pan, the ashes are nevertheless 85 continually removed from the pan and are finally discharged at a single point.

As above pointed out, the supports for the producer shell and body are so arranged that their bases are outside of and entirely 90 out of the way of the rotating parts of the ash-removing mechanism.

It will be readily understood that various changes can be made in the construction and arrangement of the parts, thus any suitable 95 means may be provided for rotating the ring; the plows may be constructed in different ways and united with the ring to rotate therewith by means other than those shown; the means of removing the ashes from the 100 rotating trough may also be varied and other changes made within the scope of the appended claims.

I claim:

1. The combination with a gas producer 105 having a stationary shell and a stationary ash pan having an upstanding edge, of a scraper rotatable within the pan and having an elevating portion for delivering the ashes over the peripheral edge of the pan, and means for rotating said scraper, substantially as described.

2. The combination with a gas producer having a stationary shell and a stationary ash pan, of a scraper member mounted for rotation within the pan and having an elevating portion extending upwardly from the bottom of the pan to the periphery thereof, a rotary trough into which the ashes are discharged from the pan, and means for rotating the trough and scraper, substantially as described.

3. The combination with a gas producer having a fixed shell and a stationary ash pan, of a scraper member rotatable within the pan and having an elevating portion for raising and delivering the ashes from the peripheral edge of the pan, a rotatable trough surrounding the pan and into which the ashes are arranged to be discharged,

means for rotating the trough and scraper, and means for discharging the ashes from the trough at a single point, substantially as described.

5. 4. The combination with a gas producer having a fixed shell and a stationary ash pan, of a scraper member rotatable within the pan and having an elevating portion for raising and delivering the ashes from the peripheral edge of the pan, a rotatable trough surrounding the pan and into which the ashes are arranged to be discharged, means for rotating the trough and scraper, and means for discharging the ashes from the trough at a single point, said means comprising a stationary plow depending within the trough, substantially as described.
5. In a gas producer, the combination with a stationary shell and pan, having an upstanding edge, of an annular member surrounding the pan, gearing for rotating said member, and a scraper carried by the annular member and extending within the pan, said scraper having means for elevating the ashes over the edge of the pan, substantially as described.
6. In a gas producer, the combination with a stationary shell and pan, of an annular member surrounding the pan, gearing for rotating said member, a scraper carried by the annular member and extending within the pan, said scraper having means for elevating the ashes over the edge of the pan, together with an annular trough surrounding the pan, and means for rotating said trough and for discharging the ashes therefrom, substantially as described.
7. In a gas producer, the combination with a stationary shell and pan, of an annular member surrounding the pan, gearing for rotating said member, a scraper carried by the annular member and extending within the pan, said scraper having means for elevating the ashes over the edge of the pan, together with an annular trough surrounding the pan, and means for rotating said trough and for discharging the ashes therefrom, said trough being supported upon rotating means journaled in the annular member, substantially as described.
8. In a gas producer, the combination with a stationary shell and ash pan, of an annular member surrounding the pan and having supporting wheels journaled therein, gearing for driving and centering said member, a scraper member carried by said annular member and extending within the pan, said scraper having an elevating portion, and a trough surrounding the pan and mounted on said wheels, said trough being arranged to be rotated by the wheels and to receive the ashes discharged from said pan, substantially as described.
9. In a gas producer, the combination with a stationary shell and ash pan, of an annular member surrounding the pan and having supporting wheels journaled therein, gearing for driving and centering said member, a scraper member carried by said annular member and extending within the pan, said scraper having an elevating portion, and a trough surrounding the pan and mounted on said wheels, said trough being arranged to be rotated by the wheels and to receive the ashes discharged from said pan, substantially as described.
10. In a gas producer, the combination with a stationary ash pan having an upstanding edge, of a pair of scrapers arranged oppositely within said pan, said scrapers having elevating portions, and an annular member surrounding the pan and to which the scrapers are connected, and means for rotating the annular member and thereby the scrapers, substantially as described.
11. In a gas producer, the combination with a stationary ash pan, of a pair of scrapers arranged oppositely within said pan, said scrapers having elevating portions, an annular member surrounding the pan and to which the scrapers are connected, and means for rotating the annular element and thereby the scrapers, together with an annular trough arranged exteriorly of the pan to receive the discharge from said scrapers, and means for rotating the trough, substantially as described.
12. In a gas producer, the combination with a stationary pan having an upstanding edge, of a pair of scrapers mounted within the pan, said scrapers having elevating portions extending to the point adjacent the peripheral edge of the pan, and means exteriorly of the pan for rotating the scrapers, substantially as described.
13. In a gas producer, the combination with a stationary pan, of a pair of scrapers mounted within the pan, said scrapers having elevating portions extending to the point adjacent the peripheral edge of the pan, and means exteriorly of the pan for rotating the scrapers, said scrapers being connected at their inner ends to a central hub member, substantially as described.
14. In a gas producer, the combination with a stationary ash pan, of a pair of scraper elements arranged within the pan and having elevating portions arranged to deliver the ashes over the peripheral edge of the pan, a central hub member to which the scrapers are connected at their inner ends, and a water outlet contained within said hub member, substantially as described.
15. In a gas producer, the combination with a stationary ash pan, of a pair of scrapers within said pan and extending in opposite directions from the center thereof,

said scrapers having elevating portions at their outer ends arranged to discharge the ashes from the periphery of the pan, an annular element surrounding the pan and to which the scrapers are connected, driving gears engaging diametrically opposite portions of the annular element, and an ash receiving trough rotatably mounted on said annular element and arranged to receive the ashes discharged by the scrapers, together with means for discharging the ashes from said trough, substantially as described.

16. In a gas producer, the combination with a stationary ash pan, of a pair of scrapers arranged oppositely within said pan, said scrapers having elevating portions, an annular member surrounding the pan and to which the scrapers are connected, means for rotating said annular member and thereby rotating the scrapers, and a trough surrounding said ash pan and receiving ashes as discharged therefrom by said scrapers, substantially as described.

17. In a gas producer, a stationary ash pan, a trough surrounding said ash pan, and means for elevating ashes over the peripheral edge of said ash pan and delivering the same to said trough, substantially as described.

18. In a gas producer, a stationary ash pan, a trough surrounding said ash pan, means for rotating said trough, means for

transferring ashes from the ash pan to said trough, and means for discharging ashes from said trough, substantially as described.

35

19. In a gas producer, the combination with a stationary pan, of a scraper mounted within the pan, said scraper having an elevating portion extending to a point adjacent the peripheral edge of the pan, means for rotating the scraper, a trough surrounding said pan, and means for rotating said trough, substantially as described.

40

20. The combination with a gas producer having a stationary shell and a stationary ash pan, of a scraper member mounted for rotation within the pan and having an elevating portion extending upwardly from the bottom of the pan to the periphery thereof, a rotary trough into which the ashes are discharged from the pan and means for rotating the trough and scraper at relatively different speeds, substantially as described.

45

21. In a gas producer, an ash pan, a trough surrounding said ash pan, means for elevating ashes over the peripheral edge of said ash pan and delivering the same to said trough, and means for moving said first-mentioned means and said trough at relatively different speeds.

50

In testimony whereof I have hereunto set my hand.

55

F. H. TREAT.
